[57] CLAIM

The ornamental design for computerized electronic robot controller, as shown and described.

DESCRIPTION

FIG. 1 is a front, left perspective view of a computerized electronic robot controller showing my new design;

FIG. 2 is a front elevational view thereof;

FIG. 3 is a right side elevational view thereof;

FIG. 4 is a top plan view thereof;
FIG. 5 is a rear elevational view thereof on a reduced scale; and

FIG. 6 is a bottom plan view thereof on a reduced scale.
